UNITED STATES PATENT OFFICE.

EDWIN W. M. BAILEY, OF AMESBURY, MASSACHUSETTS.

WINDOW-GLASS GUIDE.

Application filed June 9, 1926. Serial No. 114,712.

This invention relates to that class of window guides which are primarily designed for use in connection with the vertically sliding window glass of a closed body automobile and more particularly to that type of guide shown in my prior Patents #1,571,831 and 1,521,168, in which strips of channel form resilient metal are provided to receive the side edge portions of the glass, the sides 10 of the channel strip being adapted to be yieldably engaged, directly or indirectly, with the surfaces of the glass. To secure the benefit of the resiliency or cushioning effect of the sides of the metal channel to the 15 fullest extent, the channel should be mounted in such a manner that its sides may yield throughout the entire width thereof, and particularly at points adjacent its base portion, and where this form of guide is employed in a wooden casing, this result may 20 be secured by securing the channel to the bottom of the casing groove by screws which are passed through the base of the channel into the casing and by making the groove 25 of such width that, when the glass is in position in the channel, the sides of the channel do not bear against the sides of the groove at any point, thereby permitting the sides to yield adjacent the base to a sufficient extent to relieve the glass from strain due to 30 a sudden shock or blow.

Where, however, the metal channel is set into a groove formed in a metal casing, attachment by means of screws is impractical, 35 on account of the greatly increased expense incident to such a method. Other methods which have been considered practical, such as cementing, or clamping, involve a close engagement of the sides of the channel with 40 the sides of the groove for a substantial portion of the distance from the base thereof, amounting to approximately half the distance from the base to the edges of the sides, so that the portion of each side which 45 may then yield to relieve the shock to the glass from a sudden blow, as from the slamming of the door closed, is greatly reduced, as compared with the cushioning effect provided when the sides of the channel are 50 yieldable from edge to base.

The primary object of my present invention is to provide guiding means, of the type above indicated, which may be readily mounted in the groove of a metal casing 55 and securely attached in this position, so that a support for the glass will be provided

which will have substantially the same cushioning effect as when the metal channel is so secured that the sides of the channel do not engage the sides of the casing groove. 60

I accomplish these objects in the manner hereinafter described and as illustrated in the accompanying drawings, in which:

Fig. 1 is a combined side elevation and central vertical section of a channel guide 65 embodying a form of my invention.

Figs. 2 and 3 are transverse sections thereof.

Fig. 4 is a side elevation of the metal 70 channel.

Fig. 5 is a transverse sectional view of a modified form of the invention.

As shown in the drawing, a metal casing *a* is indicated as provided with a groove *b* of common form, the corners of the groove 75 being rounded at its bottom, to correspond to the form of the channel.

A resilient metal channel *c* is provided of the form shown in said prior patents, said channel having normally converging yieldable sides, and being lined with felt *d* in the manner indicated in my prior Patent #1,521,168, but, so far as the present invention is concerned, it is immaterial whether 80 the metal channel engages the glass directly or indirectly 85.

According to my present invention, a strip *e* of felt, or other like cushioning material, is adhesively connected to the outer surface of the metal channel *c* throughout the entire length thereof, said strip extending transversely thereof from a point approximately midway of one side of the channel about the base to a corresponding point on the other side thereof, so that the portion of the sides which is covered by the felt, or cushioning material, corresponds approximately to the portion of the sides which would ordinarily engage the sides of the casing groove when the glass *f* is inserted 90 therein, as indicated in Fig. 3.

When the metal channel is placed in position in the casing groove, the exterior of the felt strip *e* will be coated with a suitable adhesive, so that the metal channel, which has previously been adhesively connected to the felt strip, will be thereby connected to the casing. 95

With the above described construction, 100 when the glass is in position therein, although a substantial portion of the sides of the metal channel will be held in parallel 105

- relation with the sides of the casing groove, as for approximately half the width thereof, and be indirectly engaged therewith through the felt strip *e*, the resilient action or cushioning effect of the metal channel will not be substantially impaired, as it would be if this portion of the sides of the metal channel directly engaged the sides of the casing groove, for the reason that if there should be a sudden impact, which would tend to throw additional strain on either side of the channel, the felt cushion *e* would yield sufficiently to permit the entire side of the channel to yield to its base, so that the entire side of the channel, and particularly the portion thereof adjacent the base, would be effective in cushioning the glass, which would not be the case if the portion of the side of the channel which is covered with the felt cushion *e* were directly engaged with the side of the casing groove, so that only the unengaged, or outer portion of the side of the channel would be effective in cushioning the glass.
- 25 The same effect is secured with the construction shown in Fig. 5, in which a felt strip *g* is adhesively connected to each side of the metal channel from points adjacent the base to approximately the same point as in the construction previously described.
- 30 The advantages secured with the construction of Fig. 5 are practically the same as with the previous construction, in so far as the cushioning effect on the sides of the metal channel are concerned, although in some other respects it may not be as advantageous.
- 35 By employing the felt strips *e* or *g*, as described, the full cushioning effect possible of the sides of the metal channel is not only secured, but, in addition, the channel will be more effectively held in position in the casing groove by means of cement, than it

would be held directly if the metal surfaces were in direct contact. The channel may, however, be securely cemented in position when either the single wide strip *e* or the two narrow strips *g* are employed.

I claim:

1. In combination with a window glass casing having a groove, a guide for the glass comprising a resilient metal channel having its base portion secured against the bottom of said groove and its sides extending outward in convergent relation, said sides being arranged for engagement with opposite sides of the glass and adapted to yield with relation to said base, and a strip of cushioning material interposed between each side of said groove and the portions of the sides of the channel adjacent the base thereof, the sides of the strip being adhesively connected to the surfaces of the groove and of the channel with which it is held in contact, to provide a yieldable connection between the sides of the channel and the casing.

2. A window glass guide for a casing groove, comprising a metal channel having a base and resilient, normally convergent sides adapted for engagement with opposite sides of the glass, and a strip of fibrous cushioning material adhesively connected at one side to the outer surface of the channel throughout the length thereof and extending transversely about the base and onto the adjacent portion only of each side, the opposite side of the strip being adapted to be adhesively connected to the corresponding surfaces of the casing groove when the channel is in position therein, to secure the channel within groove and permit the sides of the channel to yield outward.

In testimony whereof, I have signed my name to this specification.

EDWIN W. M. BAILEY.
